UNITED STATES PATENT OFFICE.

ERNEST G. BEVERIDGE, OF BROOKLYN, NEW YORK, ASSIGNOR TO R. HOE & CO., INC., OF NEW YORK, N. Y., A CORPORATION OF NEW YORK.

COUNTING MECHANISM.

Application filed September 23, 1925. Serial No. 57,999.

This invention relates to certain improvements in counting deliveries for counting printed products as they are delivered.

It is the especial object of the present invention to produce a simple arrangement for continuously delivering products which are separated into bunches or bundles of a predetermined number, all the products of each bundle being separated from the products 5 in a preceding or succeeding bundle so that the bundles may be readily lifted off the delivery by the operator.

It is a further object of the invention to produce an improved counting mechanism in 15 which few parts are required and in which means are provided for quickly and easily changing the count.

With these and other objects not specifically referred to in view, the invention consists in certain novel parts, arrangements and 20 combinations which will be described in connection with the accompanying drawings and the novel features pointed out in the claims hereunto annexed.

25 Referring now to these drawings—

Figure 1 is an end elevation, partly broken away and partly in section, of so much of an improved counting mechanism and delivery as is necessary for an understanding of the 30 invention;

Figure 2 is a view of certain of the mechanism shown in Fig. 1, the parts being shown in a different position;

Figure 3 is a side view, partly in section, 35 of the construction shown in Fig. 1, the view being taken in the direction of arrow 3 of that figure;

Figure 4 is a detail view of an operating 40 cam for counting a certain number of products; and

Figure 5 is a similar view of an operating cam for counting a different number of products.

Referring now to these drawings, the various 45 parts of the mechanism are supported in side frames 1, 2, of any usual or desired construction, these side frames rising from a base 3. In the particular machine shown, the products are forwarded from a press or 50 other mechanism, not shown, by a pair of forwarding rolls 4, 5, mounted on shafts 6, 7, suitably supported in the side frames of the machine, before referred to. From the forwarding rolls the products drop into the 55 blades 8 of a fan delivery, these blades being

supported on an operating shaft 9, and the products are delivered from the fan on to a travelling carrier shown in the form of belts 10, on pulleys 11 on a shaft 12 extending across the machine. If desired, a spacing 60 roll 13 may be provided at suitable intervals along the belts for holding the belts in position.

In accordance with the invention, means are provided for separating the products 65 into bunches, these bunches being so spaced from each other as to permit them to be picked up by the operator, the individual products of each bunch being all separated from the products of preceding or succeeding 70 bunches. The bunches are preferably fanned out, as it were, so as to make it easy to pick them off the delivery.

While the specific means for effecting this 75 may be somewhat varied, the construction will also be such that the number of products of each bunch may be readily and quickly varied. In the particular construction illustrated, the products at the start are delivered against a fixed stop or finger 14 80 secured at one end, as 15, to one end of a bracket 16 suitably secured to the side frames of the machine. Cooperating with this fixed stop are movable counting fingers. These 85 counting fingers are arranged at the start of the delivery of each bunch to lie behind the stop finger, as shown in Figure 1. These movable stop fingers are indicated by the numeral 17 and are pivoted at 18 to the front end of the bracket 16, before referred to. 90 To effect the counting function these fingers are moved slowly forward as the products are delivered against them by the fan, the forward movement of these fingers moving the products forward on the tapes, a bunch 95 of products being collected in front of the fingers, the number of products collected depending on the speed at which the fingers move forward. This may be determined in various ways but in the preferred construction is effected by a cam, this cam being so arranged as to move the fingers forward a sufficient distance to count the desired number of products after which the finger is moved back to its initial position with a 100 quick movement so as to be in position to receive the first product of the next succeeding bunch.

While the construction for effecting this 105 may be somewhat varied, in the particular 110

construction shown the shaft 11, by which the belts are driven, has secured thereon a cam wheel 20 carrying a cam surface 21 having a high point 22. This cam is a slow moving cam and has cooperating therewith a cam roll 23 carried on a hub 24 supported on an arm 25 carried on a hub 26 mounted on a rock shaft 27 extending across the machine and suitably journaled in the side frames 1, 2, before referred to. The hub 26 is provided with a collar 27 between which and one of the side frames of the machine is a torsion spring 28, this spring surrounding the shaft. The function of this spring is to hold the cam roll in close engagement with the operating face of the cam. Also secured on a rock shaft 27 are a pair of arms 29, 30, to the outer end of which are secured one end of links 31, the other end of the links 31 being connected with the fingers 17.

With this construction it will be seen that at the start of the operation, when the parts are in the position shown in Figure 1, the cam roll has just run up the abrupt face of the high point 22 of the cam. The cam roll is held in engagement with the face of the cam by the spring 28. This abrupt movement of the roll pulls the fingers 17 rearwardly from the position shown in dotted lines in Figure 1 to the position shown in full lines, and this movement is a very quick one so that the fingers are moved back to the position shown in Figure 1 in plenty of time to engage the first product of a succeeding bunch. The roll riding on the cam forces the fingers 17 forward and effects a separation of the products, bunches of the products being fanned out as shown in Figure 1, thus making it a very simple matter to pick up a bunch of products from the tapes.

In the best constructions means are provided whereby the number of products counted may be varied to some extent and while this may be done in various ways, in the particular construction shown there is provided a second cam 32 on the shaft 12, this cam being formed with two high points 33, 34, the least number of products being counted with this cam. The cam roll 23 is slidable on the sleeve 24 and when it is desired to use the cam 32, the roll is simply slid along the sleeve so as to come into engagement with cam 32 and out of engagement with cam 21. The various parts of the machine may be driven in any suitable manner.

In the particular construction shown there is provided a driving gear 35 on a shaft 36 driven from any suitable part of the machine. Inside the gear 35 is a gear 37 which is in mesh with the gear 38 on the fly shaft 9, before referred to. This fly shaft 9, at its other end, carries a worm gear 39 in mesh with a worm wheel 40 on a short vertical

shaft 41 suitably secured in a bracket 42 secured to the side frame 1, before referred to. This shaft 41, at its other end, carries a miter gear 43 in mesh with a miter gear 44 on the cam shaft 12.

It will be seen that with this construction the belts and the cam are driven at the same speed, and a very simple and at the same time efficient counting arrangement has been provided and one in which there are few parts and in which the adjustment for varying the number of bunches is quickly and easily made.

While the invention has been described in its preferred form, it will be understood that various changes may be made in the particular construction without departing from the invention as defined in the appended claims.

What I claim is:

1. The combination with means for forwarding products, of a flat delivery to which the products are forwarded, a pusher against which the products are forwarded, means for giving the pusher a forwarding movement with the products, the extent of this forwarding movement determining the number of products forwarded against the pusher, means for effecting a quick return movement of the pusher to separate the products into bunches, and means for varying the forward movement of the pusher.

2. The combination with means for forwarding products, of a traveling flat delivery to which the products are forwarded, a pusher against which the products are forwarded, a plurality of cams with any of which the pusher may be operatively connected for giving the pusher a predetermined continuous forward movement with the products and at the speed of the products to form a product bunch, and for effecting a quick return movement of the pusher to receive the first product of a succeeding bunch, the extent of the forwarding movement depending on which cam is operating.

3. The combination with means for forwarding products, of a traveling flat delivery to which the products are forwarded, a pusher against which the products are forwarded, means for giving the pusher a predetermined continuous forward movement with the products and at the speed of the products to form a product bunch, means for varying the extent of movement of the pusher, and means for effecting a quick return movement of the pusher to receive the first product of a succeeding bunch.

4. The combination with means for forwarding products, of a traveling flat delivery to which the products are forwarded, a fixed stop against which certain of the products are delivered, a pusher engaging the products, and a plurality of cams with any of which the pusher may be operatively con-

5 nected, each of said cams having a surface
10 operating to give the pusher a predetermined
continuous forward movement at the speed
of the products and a surface for effecting
a quick return movement of the pusher be-
yond the fixed stop, the extent of the for-
warding movement depending on which cam
is operating.

10 5. The combination with means for for-
warding products, of a traveling flat deliv-
ery to which the products are delivered, a
power shaft driving the delivery, a pusher
engaging the products, a cam on the power
shaft and actuating the pusher for a pre-
determined continuous forward movement
15 until a bunch has been formed and a quick
return movement, and means for adjusting
the forwarding movement of the pusher.

20 6. The combination with means for for-
warding products, of a traveling flat deliv-
ery to which the products are delivered, a
pusher engaging the products for a prede-
termined forward movement, a shaft, a plu-
25 rality of cams on the shaft, a cam roll ar-
ranged to be brought into engagement with
any of the cams, and operating connections
between the roll and the pusher.

25 7. The combination with means for for-
warding products, of a traveling flat deliv-
ery to which the products are delivered, a
pusher engaging the products for a predeter-
30 mined forward movement, a shaft, a plu-
rality of cams on the shaft, a cam roll mov-
able widthwise of the shaft to engage any
of the cams, and operating connections be-
35

mined forward movement, a shaft, a plu-
rality of cams on the shaft, a cam roll mov-
able widthwise of the shaft to engage any
of the cams, and operating connections be-
35

8. The combination with means for for-
warding products, of a traveling flat deliv-
ery to which the products are delivered, a
pusher engaging the products for a predeter-
40 mined forward movement, a power shaft
driving the delivery, a plurality of cams on
the shaft, a cam roll movable widthwise of
the shaft to engage any of the cams and op-
erating connections between the roll and the 45
pusher.

9. The combination with means for for-
warding products, of a traveling flat deliv-
ery to which the products are delivered, a
pivoted pusher engaging the products, a cam 50
having a surface for giving the pusher a
relatively slow continuous forwarding move-
ment with the products until a product
bunch has been formed and an abrupt sur-
face for giving the pusher a quick return 55
movement, connection between the cam and
the pusher, and means for adjusting the for-
warding movement of the pusher.

In testimony whereof, I have hereunto set
my hand.

ERNEST G. BEVERIDGE.
